BOILER CLEANER

Frederick W. Linaker, St. Louis, Mo.

Application February 27, 1935, Serial No. 8,418

3 Claims. (Cl. 122—392)

My invention has relation to improvements in boiler cleaners, and it consists in the novel features of construction more fully set forth in the specification and pointed out in the claims.

The invention is primarily directed to that type of boiler cleaner wherein a blower, provided with longitudinally disposed nozzles, is disposed across a bank of boiler tubes and arranged for movement so that steam may be directed to different parts of the boiler to remove deposits from the boiler tubes. The valve casing which contains the valve for controlling the discharge of steam against the boiler surfaces has mounted on it actuating mechanism for the blower tube, and in the present instance said mechanism is arranged to rotate the blower tube by impulses, the tube remaining stationary between rotation impulses so as to permit the steam to play upon the boiler surfaces for a sufficient length of time to effectively remove the deposits therefrom.

Among the objects of the present invention are the following:

1. To provide a boiler cleaner having a single actuating means for both the steam control valve and the blower tube.

2. To embody in the blower tube rotating mechanism a ratchet device whereby said tube is rotated by steps or impulses, and comes to a complete rest between impulses.

3. To provide separate means for controlling the valve and for operating the blower tube, but associating both of said means with a single actuating means so that by moving in one direction the valve alone will be operated, and by moving in the opposite direction after the valve is operated, the blower tube alone will be actuated.

4. To completely separate the valve with its operating mechanism and blower tube operating mechanism from the blower support and from the blower head, although associating the parts for separate operation by a single means.

These objects together with the advantages inherent in the invention will be better apparent from a detailed description of the same in connection with the accompanying drawings, in which:

Figure 1 is a front elevation of my improved boiler cleaner; Fig. 2 is a side elevation of the head thereof, support, and the actuating mechanism mounted on the valve casing, the blower tube and steam supply pipe being broken away; Fig. 3 is a vertical, middle, longitudinal section taken on the line 3—3 in Fig. 1; Figs. 4 and 5 are vertical cross-sectional details taken on planes

indicated by the lines 4—4 and 5—5 in Fig. 3; Fig. 6 is a cross-sectional detail similar to that of Fig. 5, except that the valve mechanism has been actuated to open the valve; Fig. 7 is a sectional detail similar to that shown in Fig. 6 with the valve actuating mechanism restored to its "at rest" position while the valve is open; Figs. 8 and 9 are vertical cross-sectional details taken on planes indicated by the lines 8—8 and 9—9 in Fig. 3; Fig. 10 is a section similar to that shown in Fig. 9 with the valve actuating cam in position to hold the valve open; Figs. 11 and 12 are vertical cross-sectional details taken on planes indicated by the lines 11—11 and 12—12 in Fig. 3; Fig. 13 is a section similar to that shown in Fig. 12 with the blower tube actuating mechanism set to impart a rotation impulse to the blower tube; Fig. 14 is a vertical cross-section similar to Fig. 13 showing the actuating mechanism at the beginning of such rotation impulse; Fig. 15 is a vertical section similar to Fig. 14 with the actuating mechanism at the end of the rotation impulse; Fig. 16 is a section similar to that shown in Fig. 13, except that the cams and pawls of the blower actuating mechanism have been reversed to impart movement to the blower tube in a direction opposite to that in which the blower tube will rotate in Fig. 13; Fig. 17 is an elevational detail of the oscillating stop for arresting movement of the blower tube at the ends of its blowing arc; Fig. 18 is a vertical, sectional detail similar to that shown in Fig. 4, except that only the clutch for the blower tube actuating mechanism and actuating wheel hub are shown, the periphery of the actuating wheel being broken away; Fig. 19 is a diagrammatic view of the associated parts showing said parts for the at rest position of the blower; Fig. 20 is a diagram of the same parts showing their position when the operating chain has been pulled to open the steam valve, but before the blower tube has been moved; Fig. 20a is a diagram showing the positions of the parts after the operating chain has been released; Fig. 21 is a diagram of said parts showing their respective positions after the operating chain has been pulled to rotate the blower tube; Fig. 22 is a diagram of the same parts showing their respective positions after the blower tube has been moved one step along its blowing arc; Fig. 23 is a diagram of the same parts showing their respective positions after the operating chain has been pulled to effect a closing of the steam valve after the blower tube has reached its position at the end of the blowing arc; and Fig. 24 is a diagram of the same parts showing their positions

after the operating chain has been released and the valve actuating parts permitted to return to their at rest position. In this position I have the same conditions that exist in the at rest position shown in Fig. 19, except that the blower tube has been rotated through a 360° arc, and for the next blowing operation will be rotated in a direction opposite to that in which it was rotated by the operation commenced in Fig. 21. Fig. 25 is a side elevation of a modified form of my improved boiler cleaner shown applied to the boiler, part of the wall of which is shown in section; Fig. 26 is a front elevation of the modified form of boiler cleaner; Fig. 27 is a cross-sectional detail taken on the line 27—27 of Fig. 25 with the valve and blower actuating mechanism in their at rest positions; Fig. 28 is a section similar to that shown in Fig. 27 with the valve operating lever slightly moved at the beginning of the operation for opening the steam supply valve; Fig. 29 is a cross-sectional detail taken on the line 29—29 of Fig. 25 showing the pawls for actuating the blower tube ratchet in their at rest position; Fig. 30 is a cross-sectional detail taken on the line 30—30 of Fig. 25 showing the stop mechanism for limiting the movement of the blower tube actuating lever; Fig. 31 is a section similar to that shown in Fig. 27, except that the valve actuating lever has been moved to its position for fully opening the steam supply valve; Fig. 32 is a section similar to that shown in Fig. 29, except that one of the pawls for actuating the blower tube ratchet has been disengaged from said ratchet by the movement of the valve actuating lever to the position shown in Fig. 31; Fig. 33 is a section similar to that shown in Fig. 28, except that the blower tube actuating lever has been moved downwardly to effect a partial rotation of the blower tube; Fig. 34 is a section similar to that shown in Fig. 29, except that the right hand pawl has been moved to a position to impart a rotation impulse to the blower tube ratchet; Fig. 35 is a middle, longitudinal, sectional detail taken on the line 35—35 of Fig. 26 with parts broken away; and Fig. 36 is a face view of the combined ratchet and brake member.

Referring to the drawings, B indicates the wall of a boiler on which my improved boiler cleaner is mounted. According to established practice, a hollow casing 1, known as a wall sleeve, is fixed in an opening O in the boiler wall and a supporting member 2, called the wall plate, is secured by suitable bolts 3 to a flange 4 formed on the wall sleeve 1. The wall sleeve plate 2 is provided with a bracket 5 which carries the operating head A through an adjustable plate 6, coiled spring 7 and saddle member 8. The saddle member 8 has a centrally disposed boss 9 from which projects a stud 10 on which is adjustably positioned a washer 11 by means of a nut 12. The stud 10 passes through the coiled spring 7 and suitable openings 13 and 14 in the plate 6 and bracket 5, respectively, so that the weight on the operating head is resiliently supported by the spring 7.

The head A includes a supporting bracket 15 for supporting the valve casing 16 and has a flange 17 formed on its outer end on which is fixed a gear 18 so that as the gear 18 is rotated the head A will be rotated with it, the bearing saddle 8 serving as a support for the head. The bracket 15 is provided with a ring 20 on its inner end, said ring having a marginal recess 21 and 75 which, together with the opposed marginal recess

22 of a coupling member 23, forms a channel for receiving the saddle 8.

The valve casing 16 has a steam outlet branch 16' provided with a threaded opening 19, in which is screwed one end of a tubular member 19', the other end of said member passing through the ring 20 and having a conical flange 24 formed on it. Between the conical flange 24 and the ring 20 is a bearing element 25 held tightly in place by the coupling member 23, a threaded flange 23' 10 of which is screw-threaded to receive the outer end 26 of the blower tube T.

The coupling member 23 is bolted to the ring 20 by a plurality of bolts 27. Thus the bearing element 25 is frictionally held between the bracket 15 and the coupling 23 so that it will rotate with these elements while the tube 19' will remain stationary. In order to make the joint between these movable and stationary parts steam-tight, suitable packing material 28 is packed in the space behind the bearing element 25 and held in place by means of a gland 29 carried by the bracket 15 and maintained in close contact with the packing 28 by means of springs 30 disposed over studs 31 and confined between the gland 29 and a washer 32 held in place by nuts 33, 34. The construction of the boiler cleaner head which has just been described is similar to that of my copending application Serial No. 755,135, filed November 28, 1934, and will not be further described.

The valve construction of the present application is also the same as that of above said application and may be briefly described as embodying a main steam valve 35 operable in a cage 35 and a pilot valve 37 within the main valve, said pilot valve being formed on the valve stem 38, which traverses a stuffing-box 39 in the top wall 40 of valve casing 16 and also a guide bracket 41 formed integral with a supporting bracket and bearing 42 for the valve actuating and blower tube mechanism, which forms the subject-matter of the present invention and will be described hereinafter. A coiled spring 43 operates between stuffing-box 39 and a nut 44 on the valve stem 38 and, of course, is for the purpose of quickly restoring the valve to its seat when the mechanism is actuated to close the same.

The valve actuating mechanism comprises a 50 chain wheel 50 rotatably mounted on the outer end of a shaft 51 carried in the sleeve or hollow shaft 52 which is mounted in bearing 42. Within the groove 53 of said chain wheel are a plurality of equally spaced pins 54 for engaging with chain 55 by which the wheel is operated, and within the rim 56 of said wheel are a plurality (eight in the present instance) of ratchet teeth 57. A yoke 58 is mounted for rotation on the outer end of bearing 42 and on the hub 50' of chain wheel 60 50 and has a boss 59 projecting forwardly so as to come within the rim 56 of wheel 50, which boss has two sockets 60 and 61 formed in it, the former being the outermost and opening toward the chain wheel rim 56, and the latter being the 65 innermost and opening between the sides 62, 62' of the yoke. A bolt 63 is disposed in socket 60 and has a spring 64 behind it so as to constantly urge the bolt outwardly so that it will ride on the inner surface of rim 56 and engage the 70 ratchet teeth 57 thereon. A four-toothed ratchet 65 and double acting cam 66 formed integral with said ratchet is fixed to the hollow shaft 52 (or integral therewith) in the space between the sides 62, 62' of yoke 58, and a pawl 67 is pivotally 75

carried by the outer side 62' of the yoke so that its engaging part 68 will engage the teeth of the ratchet 65. The pawl 67 has a forward extension 69 in which there is a pin 70 for receiving one end of a coiled spring 71 disposed within socket 61 in the boss 59. Thus the spring 71 will keep the pawl 67 in engagement with the ratchet 65. Projecting upwardly from the bracket 41 is a lug 72, on which is pivotally mounted a lever 73, which projects laterally from its pivotal point over the valve stem 38 and against which cam 66 operates so as to take the wear which would otherwise come on the end of the valve stem.

15 The side 62' of the yoke 58 is substantially triangular in shape, at one angle of which the pawl 67 is pivoted, and at the other two angles there are points 74, 74 bent slightly inwardly so as to come in line with the outer end of bracket 41, 20 against which these points will impinge in the operation of the valve mechanism so as to serve as stop members to limit the rotation of the yoke to an angle of 90°. A coiled spring 75 is disposed about the bearing 42 and has one end 25 secured to arm 62 of yoke 58 and the other end fixed to the bracket, the purpose of which is to restore the yoke 58 to its at rest position after it has been actuated to open the valve. This 30 will be more fully explained in the operation of the invention.

The mechanism for actuating the blower tube T includes the chain wheel 50 on the outer face of the hub 50' of which is a clutch element 76 which engages clutch element 77 of the clutch member 78 when the chain wheel 50 is turned in a clockwise direction when pulling on the right hand side of chain 55. Clutch 78 is keyed or otherwise secured to shaft 51 so that the turning of the chain wheel 50 in a clockwise direction 40 will rotate the shaft 51, on the inner end of which is fixed an eccentric 79. The hollow shaft 52 terminates short of eccentric 79 and has a pair of cams 80, 81 fixed on its inner end. The eccentric 79 operates within a raceway 82 adjacent to a frame or yoke 83 encasing the cams 80 and 81 and rotatably mounted on the branch 16' of valve casing 16. The raceway 82 forms the upper part of a frame 84 which is rotatably mounted on a ring 85 formed on the outer end of bracket 15. 50 Thus the frame 83 and frame 84, being secured together at their margins by screws 86, are capable of oscillating or rocking back and forth as a single unit.

Pivottally mounted within the frame 83 below the cams 80 and 81 on pins p, p' are a pair of pawls 87 and 88 having rearwardly extending levers 89 and 90, respectively, extending beneath the cams 80 and 81 which are adapted to actuate the pawls by contact with said levers. Each pawl 60 87, 88 has a downwardly extending nose n for engagement with the teeth of the gear wheel 18 and when the pawls are not otherwise restrained they will by their own weight drop so that said nose will mesh with the teeth of said gear.

65 A stop pin 91 projects forwardly from the gear 18 and cooperates with a stop member 92 pivotally mounted on a bolt 93 fixed into the valve casing 16. The stop member 92 is in the form of a lever having its lower arm 94 operating between lugs 95, 95 projecting upwardly in spaced relation from flange f of valve casing 16. Said flange f has a second flange 96 bolted to it, into which is screwed a steam supply pipe 97.

The foregoing completes the description of the 75 construction of the main form of my improved

boiler cleaner, the operation of which will be better understood from the following description in connection with the diagrammatic views, Figs. 19 to 24, inclusive.

In the diagram Fig. 19 the operating parts of 5 the blower are shown in their at rest position, in which they are also shown in Figs. 1 to 5, inclusive, and Figs. 8, 9, 11, 12 and 17, inclusive. The valve 35 is closed and the stop pin 91 is in engagement with the stop member 92. If the 10 operator now pulls on the left side of chain 55 the wheel 50 will be rotated in a counter-clockwise direction, but the shaft 51 will remain stationary because of the lost motion or play between the clutch members 76 and 77. 15

In its rotation through 90° the wheel 50 will rock the yoke 58 through an angle of 90° because of the engagement of one of the teeth 57 with bolt 63 carried by the yoke. As the yoke 58 carries the pawl 67, this pawl will also be moved through an angle of 90° and through its engagement with ratchet 65 rotate the ratchet and the cam 66 through an angle of 90°. The rotation of the cam 66 depresses the lever 73 and valve stem 38 so as to open the valve. The valve will be 25 fully opened when the yoke 58 has moved through an angle of 90°, at which time one of the points 74 will engage with the outer end of bracket 41 to arrest any further movement of said yoke. The movement of the wheel 50 obviously is also 30 arrested at this time and the operator knows that the valve 35 is fully open. Since the hollow shaft 52 is fixed to the cam 66, the hollow shaft 52 will also rotate through an angle of 90° while the valve 35 is being opened, as just described, and 35 since the cams 80 and 81 are fixed on the inner end of shaft 52 said cams will also be rotated through an arc of 90°. Thus at the end of the 90° rotative movement of the wheel 50 the valve 35 has been opened and the respective parts have 40 assumed the position shown in the diagram Fig. 20. It will be observed that in Fig. 19 both the pawls 87 and 88 were in engagement with the teeth of gear wheel 18, but in Fig. 20 the rotation of cam 80 has caused pawl 87 to be disengaged while pawl 88 remains in engagement with the teeth of gear 18. If the operator now releases the left hand side of chain 55 the coiled spring 75 will oscillate the yoke 58 and wheel 50 back to its starting position, the other parts, however, 45 remaining unaffected (Fig. 20a).

The operator may now pull on the right hand side of chain 55 to rotate the wheel 50 in a clockwise direction (Fig. 21). During this movement of the wheel 50 the valve actuating mechanism 55 is unaffected since the bolt 63 will idle over the teeth 57 of the wheel 50. However, the shaft 51 will be rotated as will the eccentric 79 at the end of said shaft. The rotation of the eccentric 79 through one complete revolution will rock the 60 frames 83, 84 first to the left (as shown Fig. 21) when the frames have rocked to one extreme and the pawl 88 engages a tooth of gear 18, and then to the right (Fig. 22) so as to cause the pawl 88 to rotate the gear 18 in an amount equal to the 65 spacing of one tooth. A continuation of the rotation of the wheel 50 in a clockwise direction causes a continuation of the oscillating of the frame 83, 84, and every time said frame swings to the right (referring to the diagrams 21 and 70 22) the gear wheel 18 will be rotated through one tooth until finally a complete revolution of said gear is effected and further rotation is arrested by the impingement of pin 91 against the stop lever 92. After the gear wheel 18 and, of course, 75

the blower tube T have been rotated through a complete revolution the valve 35 may be closed by again pulling on the left side of chain 55, as shown in the diagram Fig. 23. The rotation of 5 the cam 66 through an angle of 90°, to effect the closing of the valve 35, also rotates the hollow shaft 52 through an angle of 90°, which changes the positions of the cams 80, 81 so that both of the pawls 87, 88 will be released to engage the 10 gear wheel 18. If the operator now releases the left side of chain 55 the yoke 58 will be restored to its normal position under the action of spring 75 and the parts are again in an at rest position, as shown in diagram Fig. 24. However, the stop 15 pin 91 is on the opposite side of the stop lever 92 from what it was in the previous at rest position (Fig. 19), and the cams 80, 81 are in neutral position so that when the valve 35 is again opened, as the first step in the operation of the 20 blower, the pawl 88 will be held out of engagement with the gear 18 and the pawl 87 will actuate the said gear in the opposite direction from that in which it was rotated to effect the previous blowing operation.

25 In the modified form of device shown in Figs. 25 to 36, inclusive, to which reference is now made, the steam supply valve is actuated by a cam 100, similar to the cam 66 of the main form, said cam 100 being formed integrally with a four-toothed ratchet 101, similar to ratchet 65, except that the ratchet 101 has a nub 102 formed on it at the base of each tooth 103. A lever 104 adjacent to ratchet 101 is rotatably mounted near the outer end of a hollow shaft 105 carried in the 30 spaced bearing brackets 106, 107 of the bracket member 108, which is secured to branch 16' of the valve casing 16. The lever 104 has a housing 109 projecting laterally from it, and a pawl 110 is pivotally mounted on a pin 111 fixed in the outermost part 112 of said housing. The pawl 110 is formed with two points 113 and 114 laterally spaced and also radially spaced with respect to the rotation axis of the lever 104, the point 114 being the outermost. The point 113 is adapted 35 to cooperate with the ratchet 101 for the actuation of the steam supply valve, as will be explained in connection with the operation of this modified form of device, while the point 114 engages with the ratchet 117. However, when the 40 lever 104 is in its idle, resting position the point 113 rests on one of the nubs 102 to hold both points 113 and 114 free from their respective ratchets. The lever 104 has a short arm 104', on the end of which is an inwardly projecting finger 45 104'' adapted to engage a projection 108' extending forwardly from the bracket member 108 so as to limit the movement of the lever 104 upwardly. On the side of the lever 104, opposite the housing 109, is a triangular projection 115 adapted to impinge on the projection 108' to limit 50 the lever 104 in its downward movement.

55 A shaft 116 is mounted within the hollow shaft 105, said shaft extending beyond the hollow shaft 105 at both the forward and rearward ends thereof. A ratchet wheel 117, having a clutch member 118 formed integrally with it, is slidably connected to or feathered on the shaft 116 a short distance from the outer end thereof, and a coiled spring 119 disposed between the hub h of wheel 60 117 and a plate 120 serves to hold the clutch member 118 in engagement with hub 121 of a second lever L keyed or otherwise secured on the outer end of hollow shaft 105. A spring S is coiled loosely around the hub 120 of lever L and 65 70 75 has one end fixed to lever 104 and the other end

fixed to lever L so as to restore said levers to their upright positions after having been pulled down. The member 118 has a socket 122 formed on the side opposite the hub h, in which socket there are equally spaced ribs 123 for cooperating with 5 similarly disposed grooves 124 on the adjacent face of hub 121 of lever L, the engaging surfaces of ribs 123 and grooves 124 being so shaped that a rotation of hub h will force the ribs out of the grooves. Of course the spring 119 yields to the lateral move of the hub h on the wheel 117. The outer end of shaft 116 is screw-threaded to receive a nut 125 which serves to hold the plate 120 in place. It will be observed (Fig. 28) that the point 114 of pawl 110 is disposed for cooperation with 10 the teeth of ratchet 117. A clevis 126 is keyed or otherwise fixed on the inner end of shaft 105, just inside the bearing 107 and above a gear 127 secured to the blower tube T in any desirable manner. Two pawls 128 and 129 are pivotally connected in spaced relation to the clevis 126 in such manner that when said pawls are allowed to drop of their own weight their points 130, 131, respectively, will engage with the teeth of gear wheel 127. However, in operating the blower 15 only one of said pawls is actuated at a time and the other pawl must be withdrawn from engagement with the gear 127.

This is accomplished by means of a member 132 that may be called a setting plate, because 30 said member is provided with lugs 133 and 134 for engagement with bosses 135, 136 of the respective pawls to move said pawls away from gear 127. The setting plate 132 is fixed on the inner end of shaft 116 so that when said shaft is actuated 35 to open or close the main steam valve the pawls 128 and 129 will be set in position to properly rotate the gear 127. An operating chain 137 is attached to the lever 104 and chain 138 is attached to the lever L. A stop member 139 is 40 fixed on the hollow shaft 105 and has lugs 139', 139'' projecting from it and spaced an amount corresponding to the throw of the lever L which is arrested either on its downstroke or upstroke by the impingement of one or the other lugs 139' 45 on the lug 141 formed on bracket 108.

The operator pulls on the chain 137 connected to lever 104 to rock said lever downwardly, and in so doing the points 113 and 114 engage ratchets 101 and 117, respectively, to rotate said ratchets 50 through an arc of 90° after which the lever 104 is arrested by the impingement of the projection 115 against the stop member 108'. As the ratchet 101 is rotated the cam 100 will also be rotated through an arc of 90° to depress the valve stem 55 38 and open the steam supply valve. The rotation of the ratchet 117 also rotates the shaft 116 and the setting plate 132 fixed on the inner end thereof so that the lug 134 will engage the boss 136 of pawl 129 to lift said pawl free from the 60 teeth of gear 127.

During the rotation of the ratchet 117 the spring 119 will hold clutch 118 in engagement with hub 121 of lever L tending to move said lever upwardly but stop member 139' will engage 65 lug 141 of bracket 108 to prevent any upward movement of the lever L. I now have the position shown in Fig. 31 with the valve stem 38 fully depressed by the cam 100 and the pawl 128 in position (Fig. 32) to impart rotative impulses 70 to the gear 127. These impulses are imparted to said gear by pulling downwardly on the right hand chain 138 after first releasing the chain 137 to allow the lever 104 to return to its uppermost position shown in Fig. 27. During this return 75

movement of the lever 104 the points 113, 114 of pawl 110 ride idly over the ratchets 117 and 101 until the lever 104 comes to rest, at which time the point 113 is resting on one of the nubs 102 so as to hold the point 114 clear of the ratchet teeth 117. The operator may now pull downwardly on the chain 138 so as to oscillate the lever L and rock the hollow shaft 105 and shaft 116 which also rocks the setting plate 132 and the clevis 126 to straighten out the joint between pawl 128 and said clevis, and thereby impart a rotation impulse to the gear 127. If the operator now releases the chain 138 the lever L will be pulled back upwardly by the spring S, restoring the clevis 126 and pawl 128 to the position shown in Fig. 32 so that the next impulse may be given. When the lever L is in its lowermost position the parts are in the positions shown in Figs. 33 and 34. Thus, every time the lever L is pulled downwardly the gear 127 is rotated an amount equal to the pitch of the teeth of gear 127.

When the blowing operation has been completed the stop pin 91 will engage the opposite side of the lug 92. The lever 104 is now rocked downwardly in the same manner as before to rotate the cam 100 through an arc of 90°, which releases the valve stem 38 and permits the steam supply valve to close. During this last movement of the lever 104 the setting plate 132 will be rotated 90° beyond the position shown in Fig. 32, which brings the lug 133 opposite to the position it occupied in Fig. 29. The next time the blower is operated the movement of the lever 104 will rotate the setting plate 132 through an arc of 90° causing the lug 133 to impinge on the pin 135 and lift the pawl 128, the pawl 129 remaining in engagement with the teeth of the wheel 127. We now have just the reverse position from that shown in Fig. 32. The pawl 128 is raised free from the teeth of the wheel 127 and pawl 129 is in engagement with said teeth. Therefore, when the lever L is actuated to rotate

the blower the blower will be advanced step by step by the pawl 129 in the opposite direction to its movement when it was actuated by the pawl 128.

Having described my invention, I claim:

1. A boiler cleaner comprising a rotatory soot blower tube, a steam valve, a swivel head, and a common means for operating the valve and rotating the blower tube, means comprising double acting opposed cam surfaces to operate the valve, 10 said means being associated with the common means which is effective thereon when moved in one direction, and a ratchet device to operate the blower tube, said device being associated with the common means which is effective thereon 15 when moved in the opposite direction.

2. A boiler cleaner comprising a rotatory soot blower tube, a valve controlling the admission of fluid thereto, mechanism for operating said blower tube, and mechanism for operating said valve, the last mechanism comprising double acting opposed cam surfaces and means for actuating said cam surfaces to advance through approximately 90° steps to control the valve, and a single operating device for successively operating 20 the second said mechanism and the blower tube. 25

3. A boiler cleaner comprising a rotatable blower tube, an operating head connected with said tube, a valve casing in communication with said blower tube, a valve in said casing, and operating mechanism carried by said valve casing; an operating sheave interconnected with both the valve and the blower tube, means associated with the operating mechanism for opening and closing the valve with a rotation of the sheave in one 30 direction, the construction and arrangement of the parts being such that a rotation of the sheave in the reverse direction operates to rotate the blower tube between the opening and the closing of the valve. 35
